EXERCISE DEVICE

George C. Sun, 801 Cooper Landing Road,
Cherry Hill, N.J. 08034

Filed Mar. 5, 1968, Ser. No. 10,858

Term of patent 14 years

Int. Cl. D21—03

U.S. Cl. D34—5

FIG. 1.

FIG. 1 is a side elevational view of an exercise device embodying my new design;

FIG. 2 is an end view showing the face configuration of one of the end members, the opposite end member being the same;

FIG. 3 is an enlarged sectional view taken on line 3—3 of FIG. 2.

I claim:

The ornamental design for exercise device, as shown and described.
